UNITED STATES PATENT OFFICE.

WILLIAM WINFIELD SMITH, OF SOUTH PORTLAND, MAINE.

BLEEDER-ROD.

1,279,770.

Specification of Letters Patent. Patented Sept. 24, 1918.

Application filed November 2, 1917. Serial No. 199,984.

To all whom it may concern:

Be it known that I, WILLIAM WINFIELD SMITH, a citizen of the United States, and a resident of South Portland, in the county of 5 Cumberland and State of Maine, have invented a new and useful Improvement in Bleeder-Rods, of which the following is a specification.

My present invention relates generally to 10 air brakes, and particularly to the air brakes of freight cars, being directed especially to the means for bleeding air from the brake cylinder after the freight cars are cut off from the locomotive. The primary object of 15 my invention is to provide a rod for bleeding brake cylinders, of such form and in connection with such means that the rod may be held indefinitely in operative position so as to avoid the necessity of its manual support while the pressure is initially 20 bled from the cylinder, and so as to obviate the danger of an accumulated pressure in the brake cylinder from leaks.

My invention proposes a rod pivotally 25 connected at one end to the vent of the brake cylinder and having an angular handle at its opposite end adjacent the car sill, to which the rod extends from the brake cylinder, the rod having certain means co- 30 operating with either a portion of the car sill or a member attached thereto, whereby the rod may be held in operative position, that is the position which will maintain the vent of the brake cylinder open, so that it 35 will be simply necessary for the operator to move the rod to operative position and lock the same, to prevent action of the brake until the rod is released.

In the accompanying drawing illustrating 40 my invention,

Figure 1 is a view illustrating the practical application of my invention, and

Fig. 2 is a detail perspective view of my improved bleeder rod removed.

Referring now to these figures, I have 45 generally indicated a brake cylinder at 10 in Fig. 1, whose release valve 11 is opened by outward upward movement of either of its arms 12. To each of these arms 12, I 50 pivotally connect the inner end of my improved bleeder rod 13, which it will be noted from Fig. 2, is in the form of a flat metal strip having an opening 14 at one end to provide for the pivotal connection with the

respective arm 12, as above described, and 55 which is twisted at 15 adjacent its opposite angular end 16, which latter extends to a point adjacent the sill of a car in connection with which the rod 13 is utilized.

The rod 13 is, moreover, intermediately 60 cut away at its lower edge to prevent an inwardly facing shoulder 17, which latter may coöperate with a portion of a car sill, or with a bracket 18, through an opening of 65 which the outer end of the rod is extended, so as to hold the rod in its outer operative position, after movement by the operator thereto, it being obvious that the weight of the rod will lower the shoulder 17 in engagement with the outer face of the bracket when 70 opposite the same.

It is furthermore, obvious that by means of the bleeder rod proposed by my invention, the necessity of manually holding the rod in operative position against the tension of the usual release valve spring, is avoided during the bleeding off of pressure when the valve is initially opened, and that I thus avoid waste of time in this way. It is furthermore, obvious that when moved to 80 operative position and locked as described, my improved bleeder rod will thereafter avoid all danger of accumulation of pressure in the brake cylinder due to leaks, which frequently happens with the result that the 85 brakes become bent and not infrequently the wheels either skid and are flattened, or the brake rigging is ripped down.

Under the above circumstances, it is further obvious that in saving time and by 90 avoiding the danger noted, my invention provides a bleeder rod capable of highly effective use for the purposes intended.

I claim:

A bleeder rod for the brake cylinder of a 95 railway car having an apertured supporting bracket depending from the base thereof adjacent its side, said rod extending at its outer end through the said bracket and having a handle beyond the bracket, and said 100 rod being provided with an intermediate cut away portion forming a shoulder for engagement with a portion of the said bracket when the rod is in outer operative position.

WILLIAM WINFIELD SMITH.
